WASHING MACHINE FIXTURE

John F. Sheerin, Stratford, Conn.

Application May 3, 1941, Serial No. 391,633

4 Claims. (Cl. 68—22)

This invention relates to washing machines, and more particularly to a combination washing machine and sink, and has for an object to provide a fixture which comprises as a unit the combination of a tub with an agitator therein operated by a motor for washing clothes and incorporated in the same fixture a sink separated from the washing machine by a dividing wall over which is mounted a wringer so that the sink may be employed for receiving the clothes from the wringer and as a second receptacle for rinsing the clothes.

A further object is to provide a device which is a stationary fixture to take the place of the usual portable washing machine and will require one less unit in the kitchen, thus saving space and protecting floors and walls. It requires no heavy pulling or pushing as is required in portable machines, and with it no hoses or pumping are necessary.

With the foregoing and other objects in view I have devised the construction illustrated in the accompanying drawings forming a part of this specification. It is however to be understood that I am not limited to the specific construction and arrangement shown, but may employ various changes and modifications within the scope of the invention.

In these drawings:

Fig. 1 is a top plan view of the unit complete;

Fig. 2 is a partial front elevation and partial vertical section to the rear of the front wall;

Fig. 3 is a vertical transverse section substantially on line 3—3 of Fig. 2 and on a larger scale;

Fig. 4 is a horizontal section of the drive for the wringer substantially in the plane of line 4 of Fig. 3;

Fig. 5 is a partial section and partial elevation of a portion of the drive for the wringer;

Fig. 6 is a partial elevation and partial section of the drive mechanism from the motor to the agitator and wringer taken substantially on line 6—6 of Fig. 7;

Fig. 7 is a partial plan view and partial section of the drive of Fig. 6 taken substantially on line 7—7 of Fig. 6;

Fig. 8 is a detail of a portion of the drive to the agitator;

Fig. 9 is a top plan view of the mounting at one end of the wringer showing the upright wall supporting it in sections;

Fig. 10 is a side elevation looking toward the bottom of Fig. 9 and showing the supporting wall in section;

Fig. 11 is a partial vertical section and partial

end elevation looking from the right of Figs. 9 and 10;

Fig. 12 is an end elevation of the upper roller in a portion of the supporting means;

5 Fig. 13 is an elevation thereof looking from the right of Fig. 12;

Fig. 14 is a vertical section through the upper end portion of the agitator showing its driving connection to the operating shaft; and

10 Fig. 15 is a transverse section substantially on line 15—15 of Fig. 14.

The device comprises a stationary unit to be permanently installed in place of the usual sink or set tubs, and has incorporated in it a sink and washing machine so that a separate portable washing machine is not required, thus saving space and doing away with the necessity of shifting a portable machine and the attendant objections to such a machine, such as injury to floors

15 by the rollers or casters and the use of hoses and pump for filling and draining. It comprises a body 1 having upright walls forming a receptacle 2 comprising a tub in which is mounted an agitator 3 of a washing machine unit for agitating

20 or working the clothes in the tub 2 in the usual manner of washing clothes in a washing machine. It also comprises a receptacle 4 forming a sink at one side of the tub 2 and separated therefrom by an intermediate partition 5 comprising spaced upright walls 6 and 7 connected at their tops by oppositely inclined walls 8. The top walls 8 are spaced below the top or rims of the tub 2 and the sink 4, and in the space thus left over the walls 8 is mounted a wringer 9 comprising upper and lower rolls 10 and 11. Faucet

25 means is provided for supplying hot and cold water to the tub and the sink, and this may include separate faucets for each receptacle or a swinging common discharge nozzle 12 for both the hot and cold water and mounted so that it may be swung to discharge into either receptacle. It is connected by the usual piping to the house water system for both hot and cold water and controlled by the hot and cold valves 13 and 14.

30 Each receptacle 2 and 4 also has an individual drain 2a and 4a controlled by suitable stoppers, not shown, and permanently connected with the usual drain pipes, also not shown, leading to the sewer system. There may also be provided a soap dish 15. The details of the valves and piping are not shown as it may comprise the standard construction and installation. The upright rear walls of the unit indicated at 16 are spaced from the rear wall 17 of the room to provide a space

out of sight and also protected from injury. The whole unit may either rest on the floor 19 or be supported the desired distance above the floor by a suitable base or bed 20 to which it may be secured by any suitable means such as the screws 21. At the rear and extending above the top wall 22 and the top rim of the receptacles may be an upright splash wall 23 to protect the wall of the room above this fixture.

The bottom wall of the tub 2 is indicated at 10 24 and is located to give the desired depth to the tub or receptacle 2, and may be spaced above the base 20 to provide a compartment 25 to mount the motor 26 and associated mechanism for connecting the motor to the agitator 3 and the wringer 9 for driving them. This motor may be an electric or hydraulic motor, usually an electric motor, and may be mounted in any suitable way such as suspending it from the underside of the wall 24. The bottom wall 27 of the sink may be located to give any desired depth to the receptacle 4, and ordinarily is at a higher level than the bottom wall 24 of the tub or washer as usually the sink is of less depth. This provides cabinet space 28 for storing various articles under the wall 27, and may have one or more shelves 29 and be closed by suitable door 30.

The agitator unit 3 may be of any suitable construction, that shown having a plurality of upright tapered ribs 31 extending laterally from the central housing 32. It is secured at its upper end to an upright shaft 33 running in suitable bearings 34 in an upright shaft housing 35 mounted on the bottom wall 24. The central housing 32 embraces the shaft housing 35 and has a bearing boss 36 at its lower end on a suitable bearing 37 on the lower end of the housing 35. Secured to the upper end of the shaft 33 is a head 38 secured to rotate with the shaft by any suitable means, such as a cross pin 39, and it also might bear on the upper end of the housing 35. In the periphery of this head are alternate upright ribs and grooves 40 and 41 in alignment with similar ribs and grooves 42 and 43 on the inner side of the housing 32. Between them is a cap 44 having side walls 45 on the inner and outer surfaces of which are ribs 46 and 47 to seat in the grooves 41 and 43 respectively to thus provide a driving connection between the head 38 and the housing 32. To disconnect the driving connection this cap may be lifted by a suitable handle 48 to raise the ribs 46 and 47 above the head 38, and it may be held in raised position by light springs 49 to disconnect the drive from the shaft to the housing. The ribs and grooves may be tapered slightly so that when the cap 44 is in the lower or driving position there is a binding action which will retain the cap in the lower or driving position. Stop screws 50 may project inwardly through the side walls of the housing 32 and extend inwardly under the overhanging wall of the head 38 so that the housing 32 and the agitator will not be lifted when the cap 34 is lifted.

The operating shaft 33 may be mounted at its lower end in a suitable thrust and side bearing 51, and immediately above this is an offset as shown at 52 to form a crank embraced by the bearing head 53 of a link 54 pivoted at 55 to the crank pin of a worm gear 56 meshing with the worm 57 on a shaft 58 connected through a suitable flexible joint 59 to the drive shaft 60 of the motor 26. It will be seen that rotation of the gear 56 acting through the crank 55 and link 54

5 connected to the crank 52, will oscillate the shaft 33 and the agitator 3 to perform the stirring and agitating operation of washing the clothes in the tub or receptacle 2. The gears 56 and 57 together with the bearing 51 at the lower end of shafts 33 and link 54 may be enclosed in a suitable housing 61 suspended from the wall 24 by any suitable means such as the screws 62.

A motor shaft 63 extends from the opposite of the motor, and through a flexible connection or joint 64 operates a worm 65 driving a worm gear 66 on the upright shaft 67 having its lower end mounted in bearing 68 carried in the housing 69 embracing the gears and the lower end of the shaft, and this housing may also be suspended by any suitable means, such as the screws 70, from an extension of the bottom wall 24. This shaft extends upwardly through a suitable bushing 71 which may have bearings for the shaft and extends through a side wall 72 projecting forwardly from the wall 73 at the front edges of the dividing walls 6 and 7 in the upper part of the space between this wall and the front wall 74. Above this wall 72 and in the space between the walls 73 and 74 is a sort of housing or bracket member 75 having an upwardly extending rear wall 76 and top and bottom walls 77 and 78. The upper end of the sleeve 71 may extend through the wall 78, and the upper end of the shaft mounted in the bearing 79 in the top wall 77, which top wall may close the top of the space between the walls 73 and 74.

30 The rollers 10 and 11 of the wringer 9 extend between the portions of wall 73 and rear wall 16 35 above the top wall 8 of the division between the tub receptacle 2 and the sink receptacle 4. The rollers are mounted at their opposite ends in suitable bearings 80 and 81 in suitable upright bearing housings 82 secured to the inner surfaces 40 of these portions of the walls 16 and 73 by any suitable means, such as the screws 83. There are 45 two of these upright housings 82 at each end of the wringer rolls and on opposite sides of the bearings 80 and 81 which may be of wood or other suitable material. The lower bearing 81 is stationary but the upper bearing 80 is slidable up and down between the housings 82 for adjustment and also to permit yielding of the upper roller 10 upwardly as various thicknesses of clothes pass between the rollers.

50 Means is provided for putting spring pressure on the upper roll. Thus at the top of each housing 82 is a hook 84 having a recess 85 in its inner side wall to receive a lug 86 on a flattened handle or lever 87, there being two of these lugs 86 on each lever to engage in the recesses 85, and they are located on opposite sides of a central tongue 88 in which is supported a loop 89 having sides 60 embracing the bearing block 80 and located in vertical grooves 90 in the sides of this block so as to retain the block in the loop. Each of the hooks 84 forms the head of a depending bolt 91, and the flanges 92 on these heads rest on the 65 tops of the housings 82 to limit downward movement of the bolts and these heads. Embracing each bolt within the housing is a strong coil spring 93 reacting against the top wall of the housing and a nut 94 threaded on the bolt. By 70 adjusting this nut the tension of the spring may be adjusted. When the wringer is not being used the lever 87 is in the horizontal position of Figs. 3, 9 and 10 on top of the roll 10 so that it does not extend above the rim or top wall of the fixture indicated at 95, and therefore the whole unit,

including the receptacles 2 and 4, may be covered and closed with a suitable cover, not shown, which may be placed in position. This cover may be hinged, or a separate cover may be placed over the device, and when in position forms a shelf or table for various operations in the kitchen; or, if preferred, individual hinged covers may be provided for each receptacle 2 and 4.

If it is desired to use the wringer for wringing clothes the free end of the lever 87 is raised, and the whole lever is pushed downward slightly against the action of the springs 93 to insert the lugs 86 in the recesses 85, the whole lever being shifted outwardly somewhat to permit this and corresponding movement of the loop 89 being permitted by the tapered groove 90 as shown in Fig. 13. Then as the lever 87 is swung toward the upright dotted position of Fig. 10, the looped end of tongue 88 will move down into the notch 96 in the top of the bearing block 80, and then as the movement of the lever is continued to the upright position the toggle action or leverage between the tongue 88 and lugs 86 will raise the hooks or heads 84 a short distance compressing the springs 93, and thus putting pressure on the upper roller 10 which will give the desired pressure for the wringing operation, and will also permit the roller to yield upwardly as required when clothes are fed between the rolls. Should the operator catch her fingers in the rolls a lateral blow on the upright 87 will cause it to immediately swing to the horizontal or releasing position to thus release the pressure on the rolls and thus permit the upper roll to move upwardly and release the hand or fingers so they are not injured.

As shown in Fig. 3 the shaft of the lower roll 11 is extended as shown at 97 through the wall 76, and secured to it is a beveled gear 98. Splined to the shaft 67 so as to be driven by the shaft but slidable on it are two beveled gears 99 and 100 connected by a sleeve 101 slidable on the shaft. Gear 99 is below the gear 98 while the gear 100 is above it, and it will be seen that if the shaft 67 is driven in one direction, when the gear 99 is in mesh with gear 98 the wringer roll 11 will be driven in one direction, and when the gear 100 is in mesh with the gear 98, the roll will be driven in the other direction. The sleeve 101 is provided with trunnions 102 each mounted in an elongated slot in the arms of the fork 103 of a lever 104 pivoted at 105 and having a handle 106 projecting through and from the front of the wall 74. When in the intermediate or full line position of Fig. 3 both gears 99 and 100 are out of mesh with the gear 98, and therefore the wringer is not being driven. By pushing downwardly on the handle 106 to the dotted line position gear 99 is brought into mesh with gear 98, and the wringer roller is driven in one direction, but by lifting up on the handle 106 gear 99 is moved out of mesh with the gear 98, and gear 100 may be brought into mesh with it to drive the wringer roll in the opposite direction. This arrangement thus provides a reversing drive mechanism for the wringer rolls. The lever 104 may be held in the intermediate non-driving position or in the upper and lower driving positions by a spring pressed ball 107 seating in suitably spaced recesses in the side of the lever.

It will thus be seen that in this device the washing machine and sink together with the wringer and operating mechanism are all assembled in a single unit or fixture which is permanently in-

stalled with the water supply and drain pipes in place of the usual sink or set tubs, and that the sink cavity or receptacle forms the rinsing receptacle operating in conjunction with the mechanical washer to receive the clothes as they pass through the wringer from the washing section and in which the clothes may be rinsed or otherwise treated, and then if desired be passed back through the wringer to the washing receptacle for further washing or other operations if desired. The inclined walls 8 under the wringer drain the water from the wringer back into the respective receptacles. Also the complete mechanism is entirely enclosed in the unit where it is protected and out of sight, and the sink may be used for any of its usual purposes as desired. It will thus be seen that this does away with the necessity of a separate portable washing machine, giving one less unit to be stored in the kitchen and making available the corresponding extra space. It thus saves space in the kitchen and prevents injury to the floors incident to rolling on it a heavy washing machine unit, and also prevents injury to walls caused by pushing a heavy unit against them. It also saves the operator from the necessity of pulling or pushing a heavy machine, and eliminates the necessity of using hoses for filling and emptying operations as the faucet arrangement supplies water directly to either receptacle and each receptacle has its own individual drain. Therefore no pumping is necessary for draining or other purposes.

Having thus set forth the nature of my invention what I claim is:

- 35 1. A washing machine unit comprising an integral one piece body having walls forming a tub and sink separated by a dividing partition formed of two laterally spaced walls and a connecting top wall, said tub being of greater depth than the sink and the dividing partition extending above the bottom of the sink but of less height than the sink, an agitator for clothes in the tub, a wringer mounted over the dividing partition, a motor mounted in the unit, and driving connections from the motor to the agitator and the wringer, the connection to the wringer being located in the partition.
- 40 2. A washing machine unit comprising integral side and bottom walls providing a receptacle forming a tub and another receptacle of less depth forming a sink, a separating means between the receptacles comprising upright spaced walls integral with the first walls forming a side wall of each receptacle and a top wall connecting said spaced walls inclined downwardly at least in one direction to drain to one of the receptacles, an agitator for clothes in the tub, a wringer mounted over said top wall, a motor beneath the bottom walls and driving connections from the motor to the agitator, a driving connection from the motor to the wringer located between the walls of the separating means, faucet means for supplying water to the tub and sink, and outlet drains leading from the receptacles.
- 45 3. A washing fixture comprising integral side and bottom walls providing receptacles forming a tub and a sink, a separating means between the receptacles comprising upright laterally spaced walls and a top wall connecting them spaced below the top edges of the side walls, an agitator for clothes in the tub, a wringer mounted over said top wall and located entirely below the top edges of the side walls of the tub and sink, a motor under the bottom walls, and driving connections from the motor to the agitator and to

said wringer, the connection to the wringer being located between the walls of the separating means.

4. A washing fixture comprising integral side and bottom walls providing receptacles forming a tub and a sink, an agitator in the tub, a separating means between the receptacles comprising upright laterally spaced walls integral with the first walls and a top wall connecting them spaced

below the top edges of the side walls thus providing a space over the said top wall, a wringer mounted in said space and of a height so that it is entirely below the top edges of the side walls, a motor, a driving connection from the motor to the agitator, and a driving connection from the motor to said wringer located between the spaced walls of the separating means.

JOHN F. SHEERIN,
